METAL SKI

Basil Lermont, New York, N. Y., assignor to Cairns Corporation, New York, N. Y., a corporation of Delaware

Application November 24, 1943, Serial No. 511,504

2 Claims. (Cl. 280—11.13)

This invention relates to improvements in skis and particularly relates to improvements in metal skis.

The manufacture and use of wooden skis has been almost universal inasmuch as such skis have the advantage of ease of manufacture, are light, strong, and have a surface which is particularly adapted to receive the waxes suitable for various snow conditions and to facilitate planing and climbing. It is conventional ski design to form the ski with a camber which acts as a cushion for the weight of the skier concentrated almost at the center of the skis and to cause a more or less uniform distribution of this weight along the ski so that the planing surface is maintained substantially flat.

While wooden skis have been generally regarded as superior to any other types of skis heretofore produced, such wooden skis have certain disadvantages. For example, the wooden surface is relatively soft and easily subject to gouging and scratching when run over harder objects in the snow. The edges of skis are used by the skier for control and in executing turns. For this purpose the bottom and sides of the ski should meet at a sharp 90° angle. Ordinary use rapidly wears the sharp control edges of wooden skis into rounded surfaces, and to the extent this happens the effectiveness of the edges for control is reduced. To prevent this loss of sharp edges it has been a common practice to attach narrow steel strips along one of the control edges of the skis. Such steel edges must be accurately aligned and recessed if on the bottom and the procedure adds considerably to the cost of the skis.

In addition to damaging of the ski by use, there is always the possibility that the skis will warp. Warping, of course would provide unequal as well as untrue planing surfaces which would make the use of the skis dangerous if not impossible. In order to avoid warping, it is necessary to provide presses and other equipment for the skis to keep them in alignment when not in use. This inconvenience also adds to the cost of skiing equipment. Not only is there danger of damage to the skis by warping, but moisture and high summer temperatures, when the skis are in storage, may cause a splitting or other deterioration of the skis with the result that they are likely to break while in use and cause serious accidents to the skier.

Numerous attempts have been made heretofore to overcome the disadvantages of wooden skis by manufacturing the skis from metal. In order to keep within the necessary weight limits, it has been necessary to make such skis of relatively

light or thin material. Such metal skis have not been successful for the reason that the metal is extremely flexible both longitudinally and transversely, making it difficult, if not impossible, to provide an adequate planing surface on the ski without producing a construction which will bend longitudinally and twist in use.

Another disadvantage of the use of metal is that the snow or ice tends to stick to the metal, thereby reducing the speed and preventing proper control of the skis.

A third disadvantage of such metal skis is that they have hard and relatively smooth surfaces and as a result the waxes used on skis will not adhere to the surface sufficiently strongly when the skis are in use.

Because of the resistance to damage and warping of such metal skis and the small amount of time and expense required in their upkeep, it would be highly desirable to make skis of metal, if the above-noted disadvantages of metallic skis could be overcome.

An object of the present invention is to provide metal skis which overcome the disadvantages of the prior types of metal skis noted above.

Another object of the invention is to provide a ski having at all times substantially the same flat planing surface.

Another object of the invention is to provide metal skis which provide a relatively rigid planing surface that is not subject to twisting or bending.

Another object of the invention is to provide metal skis in which the weight of the skier is distributed substantially uniformly along the length of the ski, thereby to reduce bending of the ski to a minimum.

A further object of the invention is to provide metallic skis in which the planing surfaces are treated to render them more receptive to and retentive of ski waxes.

Other objects of the invention will become apparent from the following description of typical forms of skis embodying the present invention.

In accordance with the present invention, I provide skis in which the planing surface is substantially flat throughout its length, except at the upturned leading end and with the exception of longitudinally extending groove in the planing surface as is customary in such skis. The element having the planing surface preferably is of channel-shape throughout its length and having a higher sidewall adjacent its center portion than at its ends in order to render the center of the ski more resistant to twisting and bending. Such a channel-shaped element has considerable

resistance to twisting and bending, but it is further reinforced, in accordance with the present invention, by means of an opposed channel member disposed between the walls of the lower or planing portion which is resiliently supported in such a manner as to distribute the weight of the skier, who stands upon the upper channel member, throughout the entire length of the ski.

More particularly, the upper channel member is pinned or otherwise secured at its forward end to the lower or planing member and is secured at its rear end to the lower member with capacity for relative longitudinal movement. Interposed between two channel members are a series of leaf springs which preferably vary in strength so that the weight of the skier is distributed substantially uniformly along the length of the ski.

With ski constructions of the type described above, twisting of the ski is reduced to a minimum by the interfitting channel members and there is little tendency of the ski to bend longitudinally inasmuch as the distribution of weight is uniform.

Such skis, if formed of aluminum or magnesium containing metal, may be anodized or otherwise treated to make waxes and other ski coating agents adhere strongly thereto.

For a better understanding of the present invention, reference may be had to the accompanying drawing in which:

Figure 1 is a plan view of a typical form of ski embodying the present invention;

Figure 2 is a view in side elevation of the ski;

Figure 3 is a view in longitudinal section of a portion of the ski illustrating the connection between the upper and lower shells; and

Figure 4 is a view in cross-section taken on line 4—4 of Figure 2.

A typical form of ski embodying the present invention may include a lower planing shell 10 of elongated formation and generally the shape of the skis heretofore commonly used having a transversely tapered or pointed leading end portion 10a that is turned or bent upwardly. The ski shell preferably is formed of a light weight metal such as, for example, aluminum, an aluminum alloy, magnesium or a magnesium alloy. The sheet is formed by stamping or bending to provide the planing surface described above and upwardly projecting side flanges 10b and 10c on opposite sides thereof providing a shell member of generally U-shaped cross-section.

As best shown in Figure 2, the side flanges 10b and 10c are higher adjacent the center of the shell than they are adjacent the opposite ends of the shell to reinforce and stiffen the shell at the mid zone which is subjected normally to greater stresses than the end zones.

As shown particularly in Figures 1 and 4, the bottom or planing surface of the shell 10 may be provided with a longitudinally extending groove 10d.

In order to form a platform for the foot of the skier and a support for the ski bindings, a second shell 11 of generally C-shaped cross-section at its center is disposed within the side flanges 10b and 10c of the bottom shell and extends from adjacent the rear end of the ski shell 10 to just short of the upwardly turned end 10a of the shell.

As shown in Figure 3, the side walls 11a of the upper shell 11 terminate short of the end of the shell and the top surface 11b is bent downwardly and forwardly to form a U-shaped portion 11c. The lower leg to the U-shaped portion 11c is received slidingly between the bottom of the

shell 10 and a plate 12 which is secured to the bottom of the shell 10 in order to permit relative movement longitudinally between the rear ends of the shells 10 and 11.

5 The forward end 11d of the shell 11 is pinned or otherwise secured adjacent the leading end 10a of the shell 10, thereby anchoring this portion of the shell 11 in position, but permitting relative movement between the shells because 10 of the sliding connection between the rear ends of these shells.

The upper shell 11 may not be sufficiently strong to support all of the weight of the skier and a series of leaf springs 13 and 14 may be interposed between the bottom of the shell 10 and the upper surface of the shell 11. As illustrated, two of such leaf springs are provided, but one or more may be used, if desired. The springs 13, 15 14, etc., may be formed of light spring metal, such as spring steel, and preferably are of unequal stiffness so as to obtain a uniform distribution of the skier's weight along the length of the shell 10. Thus, the shorter leaf spring 13 20 may be more resilient or less stiff than the spring 14 in order to compensate for the difference in lengths of these springs.

The upper ski shell 11 may be provided with a wooden platform 15 for receiving the ski bindings, if desired, and for stiffening the center portion of this shell.

30 The above-described construction has the advantage of satisfactory stiffness, that is, at least as great stiffness as a wooden ski of similar weight and also has the desirable characteristic of distributing the weight of the skier substantially uniformly along the length of the ski. A flat planing surface may be used inasmuch as the weight is distributed over the entire length of the ski. The elimination of camber in the ski 40 facilitates the manufacture and maintenance of the skis.

I give at least the lower or planing surface of the shell 10 an anodizing treatment if made of aluminum. If desired, the entire surface portions of the shells 10 and 11 can be anodized inasmuch as anodizing imparts high corrosion-resistance to aluminum as well as giving it a desirable grayish and non-metallic finish.

Anodizing consists generally in making the part to be anodized an anode in a chromic acid electrolytic bath. The chromic acid acts upon the aluminum and converts its surface portion into an aluminum oxide or aluminum hydroxide film of a depth dependent upon the duration of the treating operation. This surface film is slightly rough and porous. The porosity of the anodized finish permits the ski wax to penetrate into and adhere tightly to the planing surface.

If the skis are formed of other light metal such as, for example, magnesium, a phosphoric acid treatment may be used or a chrome paint. Such a paint or treatment with phosphoric acid provides a sufficiently uneven or roughened surface to facilitate the adhesion of wax thereto.

From the foregoing description of a typical form of ski embodying the present invention, it will be understood that the chief defects of the prior metallic skis and also wooden skis have been overcome by my invention. It will be understood, further, that skis embodying the present invention are susceptible to considerable modification, for example, in their shape and size as well as the means for distributing the weight uniformly over the surface. If springs are used as disclosed, the number and distribution of them may

be varied. Accordingly, it should be understood that the above-described embodiment of the invention is illustrative, only, and should not be regarded as limiting the scope of the following claims.

I claim:

1. In a metallic ski, the combination of a first elongated, metallic channel member having a straight base forming a planing portion, an upturned leading end, and upwardly extending sidewalls; a second shorter inverted channel member disposed between said sidewalls; means connecting the forward end of said inverted channel member to and restraining said forward end against longitudinal movement relatively to said first channel member; means slidably connecting the rear end of said inverted channel member to said first channel member; and leaf springs interposed between said channel members for distributing stresses applied to said inverted channel

member, substantially uniformly along the straight portion of said first channel member.

2. In a metallic ski, the combination of a first elongated, metallic channel member having a straight base forming a planing portion, an upturned leading end, and upwardly extending sidewalls; a second shorter inverted channel member disposed between said sidewalls; means connecting the forward end of said inverted channel member to and restraining said forward end against longitudinal movement relatively to said first channel member; means slidably connecting the rear end of said inverted channel member to said first channel member; and leaf springs of unequal length and unequal stiffness interposed between said channel members for distributing stresses applied to said inverted channel member, substantially uniformly along the straight portion of said first channel member.

BASIL LERMONT.
